CLAIM

The ornamental design for an adjustable jewelry article as shown and described.

DESCRIPTION

FIG. 1 is a perspective view of a first embodiment of an adjustable jewelry article in accordance with the present design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a perspective view of a second embodiment of an adjustable jewelry article in accordance with the present design;

FIG. 9 is a top view thereof;

FIG. 10 is a bottom view thereof;

FIG. 11 is a front view thereof;

FIG. 12 is a rear view thereof;

FIG. 13 is a left side view thereof; and,

FIG. 14 is a right side view thereof.

The elements of the design illustrated in broken lines from no part of the claimed design.

1 Claim, 2 Drawing Sheets
